(57) **CLAIM**

The ornamental design for a wood pet travel crate, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view for a wood pet travel crate shown fully assembled according to my design;

FIG. 2 is a perspective view thereof, shown with the door open;

FIG. 3 is top perspective view of the bottom panel of FIG. 1, shown separately;

FIG. 4 is a perspective view of the sides and bottom panels of FIG. 1;

FIG. 5 is a perspective view of the side panel of FIG. 4, the other side being identical;

FIG. 6 is a perspective view of the back panel, shown separately; and,

FIG. 7 is a perspective view of the front panel of FIG. 1, shown separately.
